CLAIM

The ornamental design for an article support device, as shown and described.

DESCRIPTION

FIG. 1 is a perspective view of the article support device; FIG. 2 is a top view of the article support device shown in FIG. 1;

FIG. 3 is a rear end view of the article support device shown in FIG. 2;

FIG. 4 is a front end view of the article support device shown in FIG. 2;

FIG. 5 is a bottom view of the article support device shown in FIG. 2; and,

FIG. 6 is a side view of the article support device shown in FIG. 2, the opposite side being a mirror image thereof.

The patterned surface treatment schematically depicted in FIG. 5 is continuous about the surfaces on which it is shown.
